UNITED STATES PATENT OFFICE.

CHARLES F. HELMAN, OF PIQUA, OHIO.

DESIGN FOR AN AUTOMOBILE RADIATOR EMBLEM.

Application filed October 26, 1928. Serial No. 28,652. Term of patent 3½ years.

To all whom it may concern:

Be it known that I, CHARLES F. HELMAN, a citizen of the United States, residing at Piqua, in the county of Miami and State of Ohio, have invented a new, original, and ornamental Design for Automobile Radiator Emblems, of which the following is a specification; reference being had to the accompanying drawing, forming part thereof.

Fig. 1 is a front elevation of an automobile radiator emblem, showing my new design; and Fig. 2 is a side view of the same.

I claim:

The ornamental design for an automobile radiator emblem, as shown.

CHARLES F. HELMAN.
